[57] CLAIM

The ornamental design for a playhouse, as shown and described.

DESCRIPTION

FIG. 1 is a perspective view of a playhouse showing my new design;

FIG. 2 is an enlarged scale top plan view thereof; and, FIG. 3 is an enlarged scale front elevation view thereof that is a mirror image of the left, right and rear views thereof.

The bottom is plane and unornamented.

FIG. 2**FIG. 1****FIG. 3**
